Primary Examiner — David G Muller*(74) Attorney, Agent, or Firm* — John Moetteli; Da Vinci Partners LLC(57) **CLAIM**

The ornamental design for an autoinjector, as shown and described.

DESCRIPTION

FIG. 1 is a rear view of the autoinjector.

FIG. 2 is a bottom view of the autoinjector.

FIG. 3 is a front view of the autoinjector.

FIG. 4 is a perspective view of the autoinjector.

FIG. 5 is a side view of the autoinjector.

FIG. 6 is a top view of the autoinjector; and,

FIG. 7 is another perspective view of the autoinjector.

1 Claim, 4 Drawing Sheets(56)
